UNITED STATES PATENT OFFICE

ALLEN E. OSTRANDER, OF PATERSON, NEW JERSEY, ASSIGNOR TO
AMERICAN CAR & FOUNDRY COMPANY, OF ST. LOUIS, MISSOURI,
A CORPORATION OF NEW JERSEY.

DUMP-CAR.

No. 829,733.

Specification of Letters Patent.

Patented Aug. 28, 1906.

Application filed April 4, 1906. Serial No. 309,874.

To all whom it may concern:

Be it known that I, ALLEN E. OSTRANDER, a citizen of the United States, residing at Paterson, Passaic county, New Jersey, have 5 invented a certain new and useful Improvement in Dump-Cars, of which the following is a full, clear, and exact description, such as will enable others skilled in the art to which it appertains to make and use the same, reference being had to the accompanying drawings, forming part of this specification, in which—

Figure 1 is a plan view of one-half of the dump-car embodying the features of my invention. Fig. 2 is an end elevation of the door-operating end of the car. Fig. 3 is a side elevation of one-half of the car at the door-operating end. Fig. 4 is a vertical central longitudinal sectional view through the other one-half of the car, this figure when taken with Fig. 3 showing the full length of the car. Fig. 5 is a vertical transverse sectional view through the car-body, the right-hand portion of the figure being taken on a line at approximately the bolster looking toward the end of the car and the left-hand portion of the figure being taken on a line through the hopper portion of the car looking toward the end. Fig. 6 is a plan view of 15 the underframing of one-half the car; Fig. 7 is a perspective view showing the construction of the center sills, draft-sills, and body-bolster; and Fig. 8 is a detail perspective view of the cover-plate 17.

30 This invention relates to cars, and particularly to dump-cars having hopper-bottoms.

The object of my invention is to provide a dump-car which is of simple construction and capable of carrying a very heavy load 35 and in which the entire contents of the car will be discharged when the doors of the car are opened.

Referring to the drawings, which represent the preferred form of my invention, I designates the center sills forming part of the underframing of the car, said sills consisting of 40 channels which are placed back to back for a portion of the length of the car, as shown in Fig. 6. Adjacent to the bolsters the channels which form the center sills diverge outwardly from each other and then extend 45 parallel to a point beyond the bolsters. Preferably the bolsters consist of I-beams 2, ex-

tending laterally from the center sills and connected thereto by brackets 3, the outer 55 ends of said I-beams being connected to the end sills 4 by sub side sills 5 of channel form. Each end sill is also of channel form and is connected to the side sills by brackets 6. Draft-sills 7 are connected to the end sills by 60 brackets 8 and to the projecting ends of the channels which form the center sills by means of sets of plates 9, said plates 9 being connected to the inner and outer faces of the draft-sills and center sills and the inside set 65 of plates 9 having their upper edges inclined, as shown clearly in Fig. 7. A casting 10, provided with the usual king-bolt opening, is interposed between the center sills, to which it is connected, and top and bottom cover- 70 plates 11 and 12 of substantially the shape shown in Fig. 6 are connected to the flanges of the center sills and to the flanges of the I-beams which form the bolster, thereby producing a very rigid construction, a center-bearing 13 being secured to the bottom cover- 75 plate, as shown in Fig. 5. Cover-plates or tie-plates 14 and 15 are also connected to the flanges of the center sills at that portion where they diverge for the purpose of 80 strengthening the same.

To form a platform at each end of the car, plates 16 are connected to the upper flanges of the side sills, draft-sills, and also to the end sill, and extending from the end sill to 85 the projecting ends of the center sills is a cover-plate 17, connected to the draft-sills and being bent downwardly at 18 adjacent to the bolster, so as to engage the inside faces of the draft-sills, to which it is connected by 90 rivets 19, the end of said plate 17 also being bent downwardly, as shown in Fig. 8.

The sides of the body portion of the car are constructed of plates 20, extending from bolster to bolster and having angles 21 secured 95 to their upper edges, said plates being carried by corner-posts 22, comprising angles. The angles which form the corner-posts are spaced apart by blocks or washers 23, and the lower ends of the same are connected to 100 the end of the bolster to which it is adjacent, the upper flanges of the I-beams which form the bolsters being cut away, so that the web of the beam can project between said angles, the projecting portion of the I-beam extending 105 beyond the sides of the car-body. The

car-body forms practically one large hopper, the end sheets of which are formed by inclined floor-plates 24 and 24', lapped at their meeting edges, the plate 24 being connected 5 at its upper edge to an angle 25, extending transversely from side to side of the car, and the plate 24' being connected at its lower edge to a partially-flanged plate 26, fastened to the center sills, the transversely-extending 10 angle being secured to the angles at the upper edge of the side plates by corner-plates 27. Each end sheet of the hopper is supported by inclined braces 28 and 28', consisting of angles and connected at their upper 15 ends to a plate 29, which is riveted to said end sheet, the lower ends of said braces being connected to a plate 30, which is fastened to the top cover-plate on the bolster, said braces being strengthened by a cross-piece 31.

20 For strengthening the posts 22 at the four corners of the body portion of the car inclined braces 32 are provided. These braces are preferably angles and are connected at their upper ends by means of plates 33 to the corner-posts, the lower ends of said braces being 25 connected to the outer faces of the sub side sills by rivets 34. The transversely-extending angles 25, to which the upper edges of the floor-plates 24 are connected, are supported and braced by vertical angles 35, connected thereto and fastened at their lower ends by means of plates 36 to the top cover-plate of the bolster.

As herein shown, the side plates 20 are 30 comparatively shallow, and each plate has connected to its lower edge an angle 37, having its horizontal leg projecting inwardly. The side sheets of the bottom of the hopper consist of inclined floor-plates 38 at the central portion of the hopper, inclined plates 39 at the ends of the hopper, and two pairs of doors 40 and 40', said inclined plates being connected at their upper edges to the side plates and at their lower edges to the center 45 sills, the floor portion of the hopper above the doors being formed by plates 41, which are connected to the side plates and to the floor-plates above referred to. The end sheets of the hopper are connected to the said floor-plates 39 by angles 42.

To prevent any of the contents of the car from lodging at the point intermediate the pairs of doors, this portion of the floor consists of plates 43, which are so arranged that 50 they form an inverted V to deflect the contents of the car through the door-openings. The doors are formed of plates which are strengthened by angles 44, fastened to the lower faces thereof, the lower ends of said 55 angles being pivotally connected to bearings 45, fastened to the center sills. An angle 46 (see Fig. 5) is connected to the underneath face of the upper edge of each door, and blocks 47 are secured to these angles for the purpose of connecting the door-operating chains

48 to the doors, said chains being connected at their opposite ends to winding-shafts 49, extending longitudinally of the car. The winding-shafts are supported in bearings 50, fastened to the angles 37, which are connected to the lower edges of the side plates, and to angles 51, which are connected to the floor-plates that form the side sheets of the hopper. The ends of said shafts are journaled in plates 52, connected to the corner-posts 75 and to the vertical angle-braces 35 at the door-operating end of the car, as shown in Fig. 2. A ratchet 53 is secured to the end of each winding-shaft 49, and the means for imparting rotary movement to the shafts consists of hand-levers 54, loosely mounted on the shafts and each provided with a pawl 55, which co-operates with the ratchets as the lever is actuated, retrograde movement of the shafts being prevented by pivotally-mounted 85 dogs 56, that can be locked in position by pivotally-mounted stops 57.

In order that the contents of the car may be deflected outwardly beyond the sides of the car, I prefer to provide the car with triangular-shaped plates 58, located at each side of the door-openings, so that when the doors are dropped these plates and the doors will practically form a chute. These plates are connected to the inclined floor-plates 38 and 39 and are also connected to side stakes consisting of angles 59, riveted to the side plates of the car and extending downwardly to a point below the center sills, said plates being additionally braced by channels 60 and 61, connected thereto and extending from side to side of the car. A plate 62 is connected to each pair of triangular-shaped plates, and when the door is dropped this plate 62 acts as a support for the same, 105 notches 63 being formed in the edge of said plate to provide a clearance for the blocks 47 on the door to which the door-chains are connected, the triangular-shaped plates being provided with flanges at their lower edges 110 which form an additional support for the door when it is open.

While I have used the terms "angles" and "members of channel form" in the specification and claims, it should be understood that other well-known commercially-rolled shapes could be substituted without departing from the scope of my invention.

Having thus described the invention, what is claimed as new, and desired to be secured by Letters Patent, is—

1. In a car, bolsters, channel-shaped center sills arranged back to back for a portion of the length of the car, said sills diverging outwardly adjacent to the bolsters and extending beyond the bolsters; substantially as described.
2. In a car, bolsters, channel-shaped center sills arranged back to back for a portion of the length of the car, said sills diverging 130

- outwardly adjacent to the bolsters and extending beyond the same, and tie-plates connected to the center sills at the points where they diverge; substantially as described.
5. In a car, center sills, laterally-extending members connected to said sills adjacent to their ends and forming bolsters, said center sills being arranged back to back for a portion of the length of the car and diverging outwardly adjacent to the bolsters, end sills, draft-sills connected to said end sills and to the center sills, and sub side sills connected to the bolsters and to the end sills; substantially as described.
15. In a car, a bolster, an end sill, side sills connected to said end sill and the bolster, draft-sills extending from the end sill to the bolster, platform-plates connected to the side sills and draft-sills, and a cover-plate connected to the draft-sills and being bent downwardly for a portion of its length to embrace the side faces of the draft-sills; substantially as described.
5. In a car, a body portion constructed to form one large hopper, inclined floor-plates provided with door-openings, center sills extending longitudinally of the car, doors connected to said sills for closing said openings, winding-shafts mounted in bearings which are fastened to angles that are connected to the inclined floor-plates, a connection between said shafts and doors, and means for rotating said shafts; substantially as described.
35. In a car, a body portion constructed to form one large hopper and comprising vertically-disposed side plates, inclined floor-plates connected to said side plates above their lower edges and provided with door-openings, center sills extending longitudinally of the car, doors connected to said sills, longitudinally-extending angles connected to the lower edges of the side plates, winding-shafts carried by said angles, connections between said shafts and doors, and means for rotating said shafts; substantially as described.
7. In a car, a bolster comprising a member having a web portion, and a corner-post consisting of a plurality of angles connected to the opposite faces of the web portion of said member; substantially as described.
8. In a car, bolsters, a body portion consisting of side plates, corner-posts connected to said bolsters and carrying said side plates, and inclined braces connected to the corner-posts and to the side sills of the car; substantially as described.
9. In a car, bolsters, a body portion consisting of side plates, corner-posts connected to said bolsters and carrying said side plates, inclined braces connected to the corner-posts and to the side sills of the car, angles extending from side to side of the car and connected to the side plates, and braces connected to said angles and to the bolsters; substantially as described.
10. In a hopper-bottom car, bolsters, a body portion consisting of side plates, corner-posts connected to the bolsters and carrying said side plates, inclined braces for strengthening said corner-posts, transversely-extending angles connected to the side plates, inclined floor-plates constituting the end sheets of the hopper, plates 29 connected to the outer faces of said floor-plates, braces arranged at an angle to the inclined floor-plates and connected at their upper and lower edges respectively to the plates 29 and to the bolsters, and cross-pieces connected to said braces for strengthening them; substantially as described.
11. In a car, center sills, side plates carried by corner-posts, inclined floor-plates at the ends of the car and connected to the center sills, inclined side floor-plates provided with door-openings and connected to the side plates above their lower edges, longitudinally-extending angles connected to the lower edges of the side plates, and doors pivotally connected to the center sills for closing the door-openings in the floor-plates; substantially as described.
12. In a car provided with a hopper having a door-opening formed in its floor, a door for closing said opening, angles connected to the underneath face of said door and spaced apart, center sills, bearings on said sills arranged between the angles on the doors, and pivot-pins connecting the bearings to the angles; substantially as described.
13. In a car, a body portion comprising straight sides and an inclined floor which slopes from the lower edges of the sides to the center sills of the car, door-openings formed in the floor, doors closing said openings, vertically-disposed plates arranged at each side of the door-openings and extending to the sides of the car, and side stakes extending below the lower edges of the sides and having said vertically-disposed plates riveted thereto; substantially as described.
14. In a car, a body portion comprising straight sides and an inclined floor provided with door-openings, doors closing said openings, vertically-disposed sheets arranged at each side of the door-openings and extending to the sides of the car, angles projecting downwardly from the sides of the car to a point below the center sills and having said plates connected thereto, and braces extending from side to side of the car and connected to the plates at the opposite sides of the car; substantially as described.
15. In a car, a body portion comprising straight sides and an inclined floor provided with door-openings, doors closing said openings and being pivotally connected to the center sills of the car, vertically-disposed sheets arranged at each side of the door-open-

ings, a transversely-extending member 62 fastened at its opposite ends to the lower ends of each pair of plates and acting as a support for the door when it is opened, said member 5 coöperating with the door and vertical sheets to form a chute; substantially as described.

16. A car having a hopper comprising inclined floor-plates provided with a plurality of pairs of door-openings, and plates 43 arranged between said door-openings in the form of an inverted V extending transversely of the car for preventing any of the contents of the car from remaining therein when the doors are opened; substantially as described.

15 17. A car provided with side plates having

angles connected to their lower edges, inclined floor-plates connected to the side plates at a point above the angles, angles connected to the underneath faces of said floor-plates and extending parallel to the angles on the side plates, and bearings connected to said angles for supporting a winding-shaft; substantially as described.

In testimony whereof I hereunto affix my signature, in the presence of two witnesses. 25

this 7th day of March, 1906.

ALLEN E. OSTRANDER.
